UNITED STATES PATENT OFFICE.

FRANK JOSEPH WINDER, OF BRACKENRIDGE, PENNSYLVANIA, ASSIGNOR TO THE SURFACE COMBUSTION COMPANY, INC., OF NEW YORK, N. Y., A CORPORATION OF NEW YORK.

NORMALIZING FURNACE.

Application filed October 7, 1927. Serial No. 224,716.

This invention relates to the manufacture of metal sheets and plates and more particularly to an improved method and apparatus for passing the sheets through a heat-treating furnace such as an annealing or normalizing furnace. The conventional way of passing sheets through a continuous annealing furnace is to support the sheets individually on a bed of horizontally-disposed, power-driven rollers. For certain trade requirements, the surface of the sheets must be free of all surface imperfections, such as pits or scratches. However, due to various causes, such as rough spots on the rollers, back-lash in roller-driving mechanism and possibly other causes, it is a matter of great uncertainty as to how many of the sheets passed through a heat-treating furnace having a bed of supporting rollers for the sheets will pass the inspection test. Sheets that must be rejected represent a very material loss to the mill, because even though they may be used for less exacting trade requirements nevertheless for such less exacting trade requirements, the special heat treatment to which the sheets were subjected during their passage through the annealing furnace would usually not have been necessary. It will also be appreciated that other items of loss are involved in rejected sheets such as cost of handling to mention only one item and also that sheets which do pass the inspection test are on account of the rejections relatively expensive.

The present invention has among its objects to provide improved ways and means for passing sheets through a heat-treating furnace to the end that sheets uniformly free from surface imperfections may be obtained. In accordance with this invention the sheets are passed through the heat-treating furnace in an upright position while hung from a supporting and conveying mechanism by one of their marginal edges. The conveying mechanism is preferably of the form shown in the drawings, that is to say, the conveying mechanism preferably consists of a plurality of disks arranged in longitudinally extending series, the plane of disks being at an angle to the vertical. In order that the sheets may be hung from the disks they are provided with a lateral support. This support preferably takes the form of a wing formed in a marginal edge of the sheet.

In ordinary sheet mill practice, the sheet as it comes from the rolls has a trimming allow-

ance of about one and one half inches. It is from this trimming allowance that the wing is preferably formed. However, the wing need not ordinarily be as wide as the trimming allowance but only a fractional part thereof. A wing having a width of about three quarters of an inch has been found to be wide enough for practical purposes. In other words, the bend in the sheet formed by providing the wing need not be in the main body of the sheet itself but only in that portion of the sheet which is eventually trimmed off. This is an important feature of the invention because by forming the bend within the confines of the trimming allowance, that part of the trimming allowance below the bend serves to protect the main or finished size surface of the sheet from coming in contact with the supporting disks with possibly consequent formation of surface imperfections.

For a more complete understanding of the invention reference is made to the detailed description taken in connection with the accompanying drawings forming part of this specification.

In the drawings, Fig. 1 is a view in vertical transverse section taken on line 1—1 of Fig. 5 and showing in addition to the improved sheet-conveying means forming part of this invention the preferred manner of heating the furnace chamber through which the sheets are passed.

Fig. 2 is a view in vertical transverse section taken on line 2—2 of Fig. 6 and showing in addition to the improved sheet-conveying means the construction of the cooling section of the furnace.

Fig. 3 is a fragmentary view on an enlarged scale showing the combinative association between the sheet to be conveyed and the conveying mechanism.

Fig. 4 is a plan view on a reduced scale showing the general shape of the sheet for the treatment of which the present invention has been evolved, the dotted lines indicating the trimming margin of the sheet.

Figs. 5 and 6 taken together show the relative lengths of the heating and cooling sections of the improved furnace, both views being in horizontal transverse section.

Fig. 7 is a fragmentary side elevation of the furnace shown in Fig. 5 and showing a driving means for the conveyer mechanism.

Fig. 8 is a fragmentary longitudinal vertical section taken on line 8—8 of Fig. 2 and

showing the preferred manner of supporting the guide rail above the conveying disks and also the interior construction of the ducts through which cooling fluid is circulated.

5 The ordinary sheet as it comes from the rolls is rectangular in shape, is much longer than it is wide, and is both longer and wider than in its finished condition by about $1\frac{1}{2}$ inches, to allow for trimming. In Fig. 4, letter "a" indicates the untrimmed sheet and "b" and "b'" those marginal parts or portions that are eventually trimmed off after the sheet is finished.

In accordance with this invention each 15 sheet is provided along one of its marginal edges, preferably one of its long edges, with a laterally extending wing or support as generally indicated at 10, the angularity of this wing being such that when it is disposed over 20 a suitable conveying means it will not slip off such means. The conveying means preferably takes the form of a series of disks 12 having a relatively narrow edge 14, whereby when the wing is placed over the upper run 25 of the disks the edge of each disk will be more or less confined to the apex of the angle formed by the wing.

It is preferred to so position the disks that 30 they rotate in a plane which is considerably inclined from the vertical in order to eliminate any danger of frictional contact between the main body of the sheet and the adjacent face of the disk. A satisfactory angle between the plane of the disks and the plane of travel of 35 the sheets has been found to be about 30° . A relatively narrow edge on the disk is provided by chamfering or beveling the disk on its inner face as indicated at 16. The bend between the wing and sheet is made about midway of 40 the width of the marginal portion which is reserved for trimming. As previously indicated, such trimming portion is usually about $1\frac{1}{2}$ inches wide consequently the wing will be about $\frac{3}{4}$ of an inch wide. It will now be 45 seen that the shape and position of the disks are so co-ordinated with the wing and sheet that any danger of the disks forming marks or scratches on the main body of the sheet is reduced to a minimum or entirely eliminated.

50 After the sheet has been passed through the furnace, the wing 10 is preferably bent back into the plane of the sheet to facilitate stacking or subsequent handling thereof. In view of the fact that the sheet is provided with the 55 wing after the sheet comes from the rolls, the bend is relatively stiff and hard which is a desirable condition for present purposes, as will be readily understood. On the other hand, when the sheet leaves the furnace, the bend 60 is relatively soft and may therefore be readily straightened into the plane of the sheet if so desired.

The disks 12 are mounted on the inner end 65 of individual shafts 18 which extend upward- ly and outwardly from a point within the

furnace chamber through an adjacent side wall of the chamber. These shafts are driven in unison in any suitable or preferred manner, as for example, by chain and sprocket drive generally indicated at 20. The shafts 70 are supported for rotation on the outside of the furnace chamber in any suitable manner, as by a framework generally indicated at 22.

The sheets may enter and leave the furnace through relatively narrow upright slots 24 in 75 the respective ends of the furnace chamber. These slots will be suitably flared or bevelled to permit the sheets to be readily passed therethrough as will be readily understood.

As a precaution to prevent the sheets from 80 becoming dislodged from the disks during their course of travel through the furnace, it is desirable to provide means tending to confine the sheets in position on the disks. This means preferably takes the form of a guide 85 rail, generally indicated at 26, said rail being disposed in spaced relation with respect to the upper run of the disks. The space between the guide rail and the upper run of 90 said disks provides a passage through which the bent over margin or wing of the sheet may freely pass. The guide rail is maintained in relatively fixed position with respect to the upper run of said disks in any 95 suitable manner as by means of hangers 28 affixed to the upper framework 20 of the furnace and extending through openings 32 in the roof of the furnace chamber. The guide rail is preferably of such construction as to 100 provide an angular hood as clearly shown in the drawings and more particularly in Fig. 3 thereof. For convenience of description, the guide rail may be considered as being of inverted V-shaped form. In the drawing the 105 guide rail has been shown as made from iron, this construction being preferred primarily for the reason that this type of iron lends readily itself to securement to the hangers 28.

110 It will be understood that the upper run of the disks are in longitudinal alinement and extend from one end of the furnace to the other. It will also be understood that the guide rail 26 extends in parallelism with the upper run of said disks.

115 In the drawing, the furnace chamber is shown as provided with two sets of sheet conveying mechanisms, the shafts 18 to which the disks are secured extending through opposite side walls of the furnace chamber, the 120 two conveying mechanisms being sufficiently laterally spaced from each other to permit sheets to be passed through the furnace on both conveying mechanisms at one and the same time without interference. By providing a sheet conveying mechanism of the character indicated, the furnace may obviously be made of much less width than is required in a furnace wherein sheets are passed through in a horizontal position and consequently in 125 130

addition to saving floor space, the constructional cost of the furnace is very materially reduced. It will, of course, be understood, that the furnace is of sufficient height to enable the sheets to be passed through the furnace with the bottom of the sheet elevated above the floor thereof. The present furnace construction also enables the sheets to be readily heated uniformly throughout their entire width. In accordance with this invention the heating mechanism preferably takes the form of longitudinally extending series of burners 34 and 36 arranged in vertically spaced relation, these burners being supplied with fuel in any suitable manner. The upper series of burners 34, preferably fire into a combustion chamber 38, set back into the side wall of the furnace chamber. In the particular firing arrangement shown, the burners are so constructed as to direct the burning fuel on to a bed of refractory material 40, this bed becoming incandescent and giving forth radiant heat. Instead of providing an inset combustion chamber for the lower burners 36, these burners may conveniently direct the burning gases on to a bed of refractory material 42 at the bottom of the furnace chamber. It is preferred to provide burners in both of the side walls of the furnace the more so when the furnace construction is such as to permit two parallel rows of sheets to be passed through the furnace at one and the same time.

The furnace chamber is of considerable length as indicated in Figs. 5 and 6. The major portion of the furnace chamber will be provided with heating means as aforesaid, in order to maintain the sheets at the required temperature for the necessary length of time to obtain the desired metallurgical changes in the sheet.

In Fig. 5 the letter "H" generally indicates the heating portion of the furnace, and in Fig. 6, letter "C" generally indicates the cooling portion of the furnace. In the cooling portion of the furnace, the side walls are made hollow as generally indicated at 44 to permit a suitable cooling medium to be passed therethrough. Referring to Fig. 8 it will be seen that a plurality of transverse tiles or the like are provided in order, among other things, to form a circuitous path for the cooling medium. Points of ingress and egress for the cooling medium will of course be provided. The particular construction of the cooling section of the furnace forms no part of the present invention and needs not to be further described.

It will now be seen that the present invention provides a relatively simple form of sheet conveying means whereby the sheets are enabled to be held in suspended position during their passage through the furnace chamber. By passing the sheets through the furnace chamber in the manner herein disclosed,

not only may sheets free from surface imperfections be obtained and the cost of manufacturing of the sheets thus very materially reduced, but the cost of constructing the furnace is very materially reduced. In the ordinary continuous sheet annealing furnace wherein a horizontally disposed bed of rollers is provided, not only must the roller supporting shafts be of a length to extend across the entire width of the furnace, but there must also be provided on each shaft, a considerable number of rollers in order to form suitable support for the sheets. This is in very great contrast to the present invention which requires but a single disk for each shaft and which requires but a relatively short shaft, for each disk.

Other desirable features resulting from this invention will be readily apparent to those skilled in the art.

The manner herein disclosed of passing the sheets through an annealing furnace is believed to be basically new in the art.

What is claimed is—

1. The combination with a longitudinally extending chamber, of a series of shafts extending from within the chamber upwardly and outwardly through a side wall thereof, a disk mounted on the inner end of each shaft, the tops of the disks being longitudinally aligned, said disks serving as a supporting and conveying mechanism for sheets hung thereon.

2. The combination with a longitudinally extending chamber, of a series of shafts extending from within the chamber upwardly and outwardly through a side wall thereof, a disk mounted on the inner end of each shaft, the tops of the disks being longitudinally aligned, a guide rail extending lengthwise above the disks in spaced relation therewith, said disks serving as a supporting and conveying mechanism for sheets positioned between the rail and disks.

3. The combination with a longitudinally extending chamber, of a series of shafts extending from within the chamber upwardly and outwardly thereof, a disk mounted on the inner end of each shaft, the upper run of the disks being in a straight line, an angle guide rail disposed over the disks in spaced relation therewith whereby a passageway is formed therebetween for the passage of sheets hung on said disks.

4. The combination with a longitudinally extending chamber, of a series of disks within the chamber having their upper run in a straight line and having their faces arranged in an oblique plane, means for supporting said disks, and means exterior of said chamber for rotating the disks, said disks constituting a conveying mechanism for objects suspended therefrom.

5. The combination with a chamber, of two laterally spaced series of disks extending

longitudinally of the chamber, the opposed faces of said disks forming an acute angle between them, the upper run of the disks constituting a conveyer for objects hung therefrom, and means for supporting said disks.

6. The combination of means for supporting and conveying sheets in an upright position where the sheets are provided with a bent-over marginal edge, said means comprising a longitudinally extending run of disks rotatable in a plane which is inclined to the vertical, said disks being adapted to support the sheets from their bent-over marginal edge, and supporting means for the disks comprising individual shafts therefor extending from one side of the disks.

7. A conveyer for metal sheets comprising

a longitudinally extending series of relatively sharp edged disks on which said sheets may be hung for travel lengthwise of said series, and means for supporting said disks for rotation in a plane making an acute angle with the sheet suspended on the disks.

8. A conveyer for conveying metal sheets provided with a laterally bent wing, comprising a longitudinally extending series of disks on the upper run of which said wing may be supported to hold the sheet in upright position, and means for supporting said disks for rotation in a plane making an acute angle with the sheet suspended on the disks.

In testimony whereof I affix my signature.

FRANK JOSEPH WINDER.
